(57) **CLAIM**

The ornamental design for a lavatory faucet and handle set, as shown and described.

DESCRIPTION

FIG. 1 is a perspective view of a lavatory faucet and handle set, showing our new design;

FIG. 2 is a front elevational view thereof;

FIG. 3 is a rear elevational view thereof;

FIG. 4 is a left side elevational view thereof, the right side being a mirror image of itself;

FIG. 5 is a top plan view thereof; and,

FIG. 6 is a bottom view thereof.
